(57) **CLAIM**

We claim the ornamental design for a filter core for beverage maker, as shown and described.

DESCRIPTION

FIG. 1 is a perspective view of a first embodiment of the filter core for beverage maker, showing our new, original and ornamental design;

FIG. 2 is a front view thereof;

FIG. 3 is a side view thereof;

FIG. 4 is a back view thereof;

FIG. 5 is a second side view thereof;

FIG. 6 is a top view thereof;

FIG. 7 is a bottom view thereof;

FIG. 8 is an exploded view thereof;

FIG. 9 is perspective view of a second embodiment of the filter core for beverage maker;

FIG. 10 is a front view thereof;

FIG. 11 is a side view thereof;

FIG. 12 is a back view thereof;

FIG. 13 is a second side view thereof;

FIG. 14 is a top view thereof;

FIG. 15 is a bottom view thereof; and,

FIG. 16 is an exploded view thereof.

The broken lines in the figures are for illustrative purposes only and form no part of the claimed design.

The figures illustrate two embodiments of the design. In the first embodiment shown in FIGS. 1-8, the filter core is wider overall than in the second embodiment shown in FIGS. 9-16. The upper part of the filter core in the first embodiment is not tapered. The filter openings in the first embodiment are spaced slightly wider apart and have a slightly more rectangular shape than in the second embodiment.
